HOISTING DEVICE

Frank E. Stahl, Tonawanda, N. Y., assignor to
 Columbus McKinnon Chain Company, Tonawanda, N. Y., a corporation of New York

Application January 21, 1933, Serial No. 652,844
 Renewed May 7, 1934

5 Claims. (Cl. 254—169)

My invention relates in general to hoisting devices and more particularly to a hand-operated hoisting device adaptable for use in railway box cars.

5 It is well known to those skilled in the art that it is the practice today to ship automobiles in railway box cars, and, so as to economize in space, one or both ends of the automobile is hoisted off of the floor and held suspended in a fixed position. 10 Economy in head room is of the utmost importance, and it is most desirable that the dimensions of the hoisting mechanism be as small as possible. Small cable drums are desirable, and I have found that a hand-operated hoist of the 15 worm and worm wheel type can be very conveniently used to operate the drums. It is also desirable that the hoisting devices be made a permanent part of the box car, and that they be secured to the upper part of the car so as to be 20 out of the way when not in use. This arrangement permits the car to be used for other purposes when automobiles are not being carried.

It has, however, been difficult to mount such a hoist in proper alignment with the drum shaft, 25 due to the inclination of the roof of the car.

The principal object of my invention has been to provide means for mounting the chain hoist, whereby it may be conveniently and accurately aligned with the shaft carrying the drums.

30 Another object has been to provide a hoisting device which can be permanently secured in place and be made a part of the box car.

Moreover, my invention makes it possible to easily and quickly assemble the hoisting mechanism within the box car with the assurance that when the hoist is fastened in place it will run freely and will not bind as a result of being out of alignment.

40 Furthermore, my invention is simple and inexpensive to manufacture.

The above objects and advantages have been accomplished by the device shown in the accompanying drawing, of which:

Fig. 1 is a front elevation of my complete device.

Fig. 2 is an end, sectional elevation, taken on line 2—2 of Fig. 1.

Fig. 3 is a similar sectional view, taken on line 3—3 of Fig. 1.

50 Fig. 4 is an enlarged, perspective view of the hoist supporting bracket.

Referring to the drawing, my hoisting device comprises a shaft 10 which is rotatably mounted in suitable bearing brackets 11 and 12. The top flange 13 of each of these brackets is inclined as

shown in Fig. 1, the inclination being that of the roof of the box car which is illustrated by the lines 14 in Fig. 1. The inclination of the two brackets 11 and 12 are opposite to correspond to the inclination of the roof of the car. Each bracket is also preferably provided with a vertically arranged flange portion 15 which is fitted against the end wall of the box car. The flanges 13 and 15 are provided with suitable apertures whereby they can be permanently secured in place 10 to the roof and end wall of the freight car. Rigidly mounted upon the shaft 10 and preferably near each of the bearing brackets 11 and 12 is a wire rope or cable drum 20. These drums may be identical if desired, but are preferably provided with grooves extending from opposite sides of the hoist, as shown in Fig. 1. For convenience of illustration, the wire rope or cable has been omitted and is shown diagrammatically, only, by broken lines at 19.

20 Any suitable hoisting mechanism which is compact enough may be attached to the end of the shaft 10 which is preferably extended outwardly a considerable distance beyond the bearing bracket 12. I have found, however, that a hand hoist 21 of the worm and worm wheel type is the most suitable for this purpose. This hoist is of the type having a casing 22 within which the worm and worm wheel (not shown) are mounted. A hand chain wheel 23 is provided on this type of 30 hoist over which a hand chain shown in a diagrammatic manner at 24 is passed.

The hoist 21 is suspended from the car roof 14 by means of a hoist supporting bracket 25. This bracket is provided with a top flange 26 and 35 with a vertical flange 27. The top and vertical flanges are arranged at such an angle to each other that when the top flange 25 is secured to the roof of the car, the vertical flange will lie in a substantially vertical plane or parallel to the 40 vertical face of the casing 22 of the hoist. The vertical flange 27 of the bracket carries attachment pads 28 and 29 each of which have an elongated slot 30 (Fig. 4). When the parts of my device are assembled, these pads will engage suitable attaching ears 31 formed on the casing 22 of the hoist and a bolt or stud 32 is passed through each of the slots 30 and into or through the ears 31, whereby the hoist casing 22 is securely attached to the hoist supporting bracket. Because 50 of the provision of the slots 30, the bracket 25 may be secured to the car roof before being attached to the hoist, and the hoist is then properly aligned and secured to the bracket. It will thus be clear that all time and labor in shimming of 55

the bracket 25 is avoided because of the provision of the slots 30, which permit easy and perfect alignment of the shaft and hoist as well as permanent securement thereof to the box car.

5 It will be clear that the coating surfaces of the pads 28 and 29, and the ears 31 of the hoist casing may be serrated so as to prevent slippage due to vibration. This and other modifications of the details herein shown and described may be 10 made without departing from the spirit of my invention or the scope of the appended claims, and I do not, therefore, wish to be limited to the exact embodiment herein shown and described, the form shown being merely a preferred embodiment 15 thereof.

Having thus described my invention, what I claim is:

1. A hoisting device comprising a shaft, bearings for rotatably supporting the shaft, said 20 bearings being secured to a supporting surface above the shaft, hoist drums mounted upon the shaft, one end of the said shaft protruding beyond the bearing therefor at that end, a chain hoist mounted upon the protruding end of the shaft, and a hoist supporting bracket carried by the supporting surface, separate from the bearing, and adjustably secured to the hoist.

2. A hoisting device comprising a shaft, bearings for rotatably supporting the shaft, said 30 bearings being secured to a supporting surface, hoist drums mounted upon the shaft, one end of the said shaft protruding beyond the bearing therefor at that end, a chain hoist mounted upon the protruding end of the shaft, and a hoist supporting bracket carried by the supporting surface and 35 adjustably secured to the hoist, said bracket comprising a top attaching flange, and a vertically

arranged flange, the vertically arranged flange being formed with elongated slots, and fastening means passing through the slots and secured to the casing of the hoist.

3. A hoisting device comprising a shaft, bearings for rotatably supporting the shaft, said bearings being secured to a stationary supporting surface, hoisting drums mounted upon the shaft, one end of said shaft protruding beyond the bearing therefor at that end, a chain hoist mounted 10 upon the protruding end of the shaft, and a hoist supporting bracket carried by the supporting surface, separate from the bearings, and secured to the hoist.

4. A hoisting device comprising a shaft, a bearing for rotatably supporting one end of the shaft, said bearing being secured to a supporting surface, hoist drums mounted upon the shaft, a chain hoist mounted upon the other end of the shaft, and a hoist supporting bracket separate 20 and spaced from the bearing and carried by said supporting surface, said bracket being secured to the hoist.

5. A hoisting device comprising a shaft, a bearing for rotatably supporting one end of the 25 shaft, said bearing being secured to a supporting surface, hoist drums mounted upon the shaft, a chain hoist mounted upon the end of the shaft which is opposite to the bearing, and a hoist supporting bracket carried by the supporting surface and 30 adjustably secured to the hoist, said bracket comprising a top attaching flange and a vertically arranged flange, the vertically arranged flange being formed with elongated slots, and secured to the casing of the hoist.

FRANK E. STAHL.
